UNITED STATES PATENT OFFICE

CRAWFORD J. WALKER, OF INDIANAPOLIS, INDIANA

FILING FOLDER

Application filed January 8, 1932. Serial No. 585,527.

This invention relates to the art of filing folders and has for its primary object the providing of a folder particularly adapted for use in connection with collection accounts wherein a follow-up indicator is incorporated together with means for a permanent progressive record of an account in addition to being adapted to receive and hold correspondence or other papers relating to the account.

10 Other objects and advantages will become apparent in the following description of the invention. Reference is made to the accompanying drawings illustrative of the invention, in which

15 Fig. 1 shows the front of a folder embodying my invention and Fig. 2, a view of the interior of the folder. Like characters of reference indicate like parts in the two views.

20 I form a folder by bending a sheet of suitable material along a fold 9 to have a front page 10, inner pages 11 and 12, and a rear page 13. The front page has numbers printed consecutively along the top margin indicating days in a month. A space is left below 25 these numbers in which the name of the creditor and other data concerning him may be entered. The underside of this space is defined by a horizontally disposed slit 14 cut through the sheet on which pages 1 and 2 appear.

30 This slit terminates before reaching the edge of the sheet so that the part of the page above the slit remains tied to the part below. I place a flattened endless band 15 about the portion of the page above the slit

35 14 to have the band pass over the top edge of the page and through the slit. The width of the band is just sufficient to cover any one number along the upper page margin. Preferably, the upper end of the band is colored 40 differently from the folder material so that its position along the folder edge may be readily recognized, particularly when the folder is one of a number of other similar folders in a filing cabinet.

45 The portion of page 1, which is below the horizontal slit 14 and which constitutes the major portion of the page is divided into vertical columns with the headings in sequence as indicated in Fig. 1, of "Month", "Monthly 50 statement balance", "Total purchases for

month", "Delinquent balances", "Date", "Cash", "Credit", and "Memo". The columns to the right of the column headed "Total purchases for month" are ruled horizontally thereacross with heavy lines defining minor or lighter lines therebetween, the space between heavy lines being intended for entries therein for the particular month as indicated in the first column.

55 Pages 2, 3 and 4 are ruled similarly to duplicates of that part of page 1 which is below the slit 14, page 2 having the same space above the slit 14 as does page 1 for the creditor's name and other data. That part of the folder forming pages 3 and 4 has its upper edge cut off so that its page height is less by about a quarter of an inch than are pages 60 1 and 2, the purpose of the lesser height being to allow the band 15 to be readily observed without being concealed by the back of the 65 folder particularly when a number of the 70 folders are filed together. A margin 16 is left across the top of page 3 to indicate a 75 space to which correspondence or other papers 17 may be attached such as by staples 18. Of course, such papers may be loosely inserted in the folder between pages 2 and 3, but a permanent file is created by fixing the papers 80 to the folder.

To illustrate the method of using the folder, 85 assuming that an account is being placed on the folder for the first time in July and that account includes items which should have been paid in the previous May, the names of the months beginning with May are written 85 consecutively down the first column, page 1, Fig. 1, with one name between adjacent heavy lines carried across the column. Taking the amount of the July statement to the creditor as being \$37.50 that amount is placed in the 90 "Monthly statement balance" column on the line to the right of the month of July. In that statement was included the sum of \$15.00 which should have been paid in May. This delinquent balance of \$15.00 is accordingly placed on the top line opposite the month of May under the column "Delinquent 95 balances". Also included in the \$37.50 balance was a sum of \$22.50 which should have been paid in June and the amount of \$22.50 100

is placed in the "Delinquent balances" column opposite the month of June. Thus the monthly statement balance has been analyzed by placing the delinquent portions thereof back under the months when first payable.

5 During the month of August, a \$5.00 cash payment was made on the account on August 2 applying on the first delinquent balance, and this amount is placed in the "Cash" column 10 and the delinquent balance then becomes \$10.00 for May and is so indicated. During the month of June, the account showed a credit for goods returned of \$12.50 on the June delinquent balance and this amount is entered 15 in the "Credit" column opposite the month of June to cut down the June delinquent balance to \$10.00 which balance is entered as the balance still due for June. Also, the account shows purchases made during August 20 to come to \$12.00 and this amount is entered in the "Total purchases for month" column opposite the month of August. The monthly statement balance for August is then the sum of the remaining May and June delinquent 25 balances of \$10.00 and \$10.00 respectively plus the purchases for the month of \$12.00 to give a total of \$32.00. This amount is entered in the "Monthly statement balance" opposite the month of August and is that amount 30 which should be billed the creditor. The band 15 is shifted along the top of the folder to over that date on which the account should be followed up for collection or other attention. Copies of correspondence relating to 35 the account are fixed in the folder over page 3, so that the folder then represents in one compact form the complete record of the creditor's account as to payments and correspondence. The folder by continuing the 40 form of page 1 over onto the other three pages provides sufficient space to carry the account in the one folder for a considerable length of time.

45 By combining the signal band 15 directly with the folder, there is no need for a follow-up card or other means separate from the filing folder, filing space is reduced, and the entire record of the account is visible at a glance.

50 I claim:

1. A filing folder comprising a sheet of material folded transversely to form a front and inside page to one side of the fold and an inner and back page to the other side of 55 the fold, the part of the sheet forming the back fold being of less height than that of the front portion, the front portion having a slit cut therethrough spaced back from and parallel to a marginal edge thereof, and a 60 signal band having one end hooked over said marginal edge and the other end hooked through said slit so as to be shiftably retained on said portion.

65 2. A collection filing folder comprising a folded sheet having a front and a rear portion

hinged together about a fold line, at least five vertical columns on the front portion designated for entry to indicate separately therein of a month, a monthly statement balance, total purchases for a month, date, cash received, and credits, and horizontally lined with major lines with minor lines therebetween on which said entries may be entered, and a space indicated on the inner side of said rear portion for attaching correspondence thereto. 70

3. A collection filing folder comprising a folded sheet having a front and a rear portion hinged together about a fold line, at least five vertical columns on the front portion designated for entry to indicate separately therein of a month, a monthly statement balance, total purchases for a month, date, cash received, and credits, and horizontally lined with major lines with minor lines therebetween on which said entries may be entered, 80 and a space indicated on the inner side of said rear portion for attaching correspondence thereto, said front portion having a slit cut thereacross spaced back from a marginal edge thereof, and a signal member engaging through said slit to be shiftable therealong. 85

4. A collection filing folder comprising a folded sheet having a front and a rear portion hinged together about a fold line, at least five vertical columns on the front portion designated for entry to indicate separately therein of a month, a monthly statement balance, total purchases for a month, date, cash received, and credits, and horizontally lined with major lines with minor lines therebetween on which said entries may be entered, 90 and a space indicated on the inner side of said rear portion for attaching correspondence thereto, said front portion having a slit cut thereacross spaced back from a marginal edge thereof, and a signal member engaging through said slit to be shiftable therealong. 95

5. A collection filing folder comprising a folded sheet having a front and a rear portion hinged together about a fold line, at least five vertical columns on the front portion designated for entry to indicate separately therein of a month, a monthly statement balance, total purchases for a month, date, cash received, and credits, and horizontally lined with major lines with minor lines therebetween on which said entries may be entered, 100 and a space indicated on the inner side of said rear portion for attaching correspondence thereto, said front portion having a slit cut thereacross spaced back from a marginal edge thereof, and a signal member engaging through said slit to be shiftable therealong, 105

110 said marginal edge having characters therealong adapted to be covered by said member, and said rear portion having its marginal edge opposite said marginal edge of the front portion cut away for a short distance therefrom.

5. A filing folder for accounts comprising a sheet of material folded once to form four pages, a printed form on each page of like nature in which an account in analyzed form may be entered and continued from page to page, and a follow-up signal attached to the front page comprising a member engaging over a marginal edge thereof, and also through a slit in the page, said form being located on the third page to leave room thereabove for attaching papers to the page. 115

6. A filing folder for accounts comprising a sheet of material folded once to form four pages, a printed form on each page of like nature in which an account in analyzed form may be entered and continued from page to 120

125

130

page, and a follow-up signal attached to the front page comprising a member engaging over a marginal edge thereof and also through a slit in the page, said form being located on 5 the third page to leave room thereabove for attaching papers to the page, and said third and fourth pages being cut off along that marginal edge under that edge of the first page over which said signal member engages.

10 In testimony whereof I affix my signature.
CRAWFORD J. WALKER.
